UNITED STATES PATENT OFFICE.

LEANDER M. MAYNE, OF WINDER, GEORGIA.

PACKAGE-TIE.

1,280,060.

Specification of Letters Patent. Patented Sept. 24, 1918.

Application filed December 15, 1917. Serial No. 207,291.

To all whom it may concern:

Be it known that I, LEANDER M. MAYNE, a citizen of the United States, residing at Winder, in the county of Barrow and State 5 of Georgia, have invented new and useful Improvements in Package-Ties, of which the following is a specification.

The present invention contemplates generally improvements in that class of inventions known as buckles, buttons and clasps, and more particularly has reference to a package tie.

It is the primary aim and object of this invention to provide a device of the above 15 character designed for use in conjunction with a piece of cord for securely fastening the cord, subsequently to the wrapping of the cord about the package of letters or the bundle, and serves to securely hold the 20 cord while the package is being transmitted, and in addition permits of the ready release of the cord when it is desired to untie the package.

More particularly this invention embraces 25 the provision of a device of the above mentioned character wherein the body is suitably reinforced, while the reinforcement in turn serves to also brace the spring retaining member.

Among the other aims and objects of this 30 invention may be recited the provision of a device of the character mentioned wherein the parts are few, the construction simple, the cost of production low and the efficiency high.

Other improvements and novel details in 35 the construction and arrangement of the various parts of the apparatus will be brought out more in detail in the description to follow, which for a clear understanding 40 of the invention should be considered in connection with the accompanying drawings forming a part hereof, and wherein is disclosed for the purpose of illustration a convenient and satisfactory embodiment of the 45 invention. It is to be noted in this connection that minor changes in the construction and arrangement of parts may be made without departing from the principle of operation of the various parts.

The invention is clearly illustrated in the accompanying drawings in which:

Figure 1 is a perspective view of the device when in use.

Fig. 2 is a top plan view of the package 55 tie.

Fig. 3 is a side elevation thereof.

Fig. 4 is a transverse section taken on line 4-4 of Fig. 2, in the direction in which the 60 arrows point.

Fig. 5 is a longitudinal section taken on the line 5-5 of Fig. 2 in the direction in which the arrows point.

Similar characters of reference are employed in all of the above described views, 65 to indicate corresponding parts.

Referring now, more particularly, to the accompanying drawings, there is provided a plate or body 1 formed of suitable metal, and being preferably of rectangular configuration, and also provided near its respective extremities with openings 2 and 3, while mounted in the opening 3 is an eyelet 4. The opening 2 serves as a means for hanging a plurality of devices on a suitable 70 support, such as a nail, not shown, while a cord 5 is designed to have one end secured through the eyelet and the other opening. The plate or body is also formed on its upper face and near the side edges, with spaced 75 parallel and longitudinally extending reinforcing ribs 6 preferably pressed in the plate when the plate is being cut. Also formed longitudinally and medially on the plate on the upper surface thereof is another rib 7 for the purpose which will presently appear. The respective ends of all of the ribs are tapered to points 9 while the ribs 6 terminate short of the end edges and the ribs 7 terminate short of the openings 80 2 and 3, as is apparent upon reference to Fig. 1 of the drawings.

Cooperating with the medial ribs 7 is an immediate retaining spring member indicated in its entirety by the numeral 10. 95 This spring member is preferably formed from a single piece of resilient wire which is bent into substantially U-shape form to provide an intermediate portion or vertex 11 and spaced side arms 12. The extreme 100 free ends of the arms are arranged upon the adjacent inner faces of the ribs 6 near one end thereof and are secured thereto preferably by solder 13. The arms are offset upwardly as indicated by the numeral 14 at 105 points near the inner ends and in proximity to one end of the ribs 7, while the portions 15 continuing from the off-set portions are

gradually inclined toward the plate and about the plate as indicated at a point 16 near the opposite end of the rib 7. Finally the arms are bent upwardly to provide a 5 guide which coöperates with the adjacent pointed end of the rib, the upwardly extending portions 17 of the arms of course being positioned approximately opposite the pointed ends 9 of the rib as indicated 10 in the drawing.

In use the plate is positioned upon the top of the package while the cord 5 is extended longitudinally about the package and is passed beneath the spring and drawn 15 inwardly between the arms and the ribs 7 so as to be bound between the offset portions 14 and the outer surfaces of the ribs. This binding engagement of the cord is accomplished of course by extending a portion of 20 the cord transversely between the arms 11 and the ribs 7. The cord is now extended transversely about the package and is again passed between the arms 11 and the rib and drawn inwardly so as to be frictionally retained 25 by the arms and the rib as indicated in Fig. 1. The package of course is now ready to be transmitted and when it reaches its destination, it may be untied by removing the cord from between the arms and the 30 rib, removing the transversely extending loop and again removing the cord from between the arms and the rib.

It is believed that in view of the foregoing description that a further detailed description of the operation of the invention is 35 entirely unnecessary. Likewise it is believed that the advantages of the invention will be readily apparent.

Copies of this patent may be obtained for five cents each, by addressing the "Commissioner of Patents, Washington, D. C."

What is claimed as new and desired to be secured by Letters Patent is:—

A package tie including a plate formed near one end with an opening, a pair of spaced parallel raised ribs formed longitudinally of the upper surface of the plate near the opposed side edges thereof, a medial 45 raised rib formed longitudinally of the upper surface of the plate and positioned between and parallel with the other ribs but terminating short of the respective ends thereof, the respective ends of all of the 50 ribs being pointed, a U-shaped spring member formed from a single piece of wire embodying an intermediate portion and spaced side arms, means for securing the outer ends of the side arms to the adjacent faces of 55 the first mentioned ribs near one end thereof so that the U-shaped member will straddle the intermediate rib, the arms being offset upwardly at a point near the inner end of the medial rib and thence gradually inclined to a point near the opposite end of the medial rib and contacting with the plate, the arms near the intermediate portion being extended upwardly to form a 60 guide for coöperating with the opposed pointed end of the medial rib and a cord having one end connected in the opening and adapted to have its main portion transversely arranged between the offset portions of the arms and the rib so as to be frictionally engaged and retained subsequently to being passed transversely and longitudinally about a package.

In testimony whereof I affix my signature.

LEANDER M. MAYNE.
